Primary Examiner — John Windmuller*(74) Attorney, Agent, or Firm* — Edwards Wildman Palmer LLP; David J. Silvia; Adam P. Daniels**CLAIM**

The ornamental design for an anchor for blanket, as shown and described.

DESCRIPTION

FIG. 1 is a front perspective view of the invention.

FIG. 2 is a rear perspective view thereof.

FIG. 3 is a front view thereof.

FIG. 4 is a left side view thereof.

FIG. 5 is a back view thereof.

FIG. 6 is a right side view thereof.

FIG. 7 is a top view thereof; and,

FIG. 8 is a bottom view thereof.

The broken lines in FIG. 5 depict portions of the anchor that form no part of the claimed design.
